UNITED STATES PATENT OFFICE.

EDWARD HUTCHENS, OF MILWAUKEE, WISCONSIN, ASSIGNOR TO FEDERAL RUBBER
MFG. CO., OF MILWAUKEE, WISCONSIN.

DESIGN FOR A RUBBER MAT.

44,890.

Specification for Design.

Patented Nov. 18, 1913.

Application filed September 19, 1913. Serial No. 790,802. Term of patent 7 years.

To all whom it may concern:

Be it known that I, EDWARD HUTCHENS, a citizen of the United States, residing in Milwaukee, in the county of Milwaukee and State of Wisconsin, have invented a new, original, and ornamental Design for a Rubber Mat, of which the following is a specification, reference being had to the accompanying drawings, forming part thereof.

Figure 1 is a plan view of a portion of a rubber mat showing my new design; and Fig. 2 is a sectional side elevation of the same on the line 2—2 of Fig. 1.

I claim:

The ornamental design for a rubber mat as shown.

EDWARD HUTCHENS.
